United States Patent Office

Des. 229,581

Patented Dec. 11, 1973

229,581

MICROSCOPE

John T. Armbruster, Niagara Falls, N.Y., and Adolf Kenzian, Vienna, Austria, assignors to American Optical Corporation, Southbridge, Mass.

Filed Mar. 26, 1973, Ser. No. 345,048

Term of patent 14 years

Int. Cl. D16—08

U.S. Cl. D57—1 E

FIG. 1

FIG. 2

FIG. 3

FIG. 4

FIG. 1 is a left front perspective view of the microscope embodying our new design;

FIG. 2 is a front perspective view of the microscope as seen from the right side thereof;

FIG. 3 is a rear plan view thereof; and

FIG. 4 is a top plan view of the microscope.

We claim:

The ornamental design for a microscope, as shown and described.
